ADHESIVE DISPENSING APPARATUS FOR
BRUSHMAKING MACHINES

Roy M. Harwell, Sr., West Gastonia, N. C.

Application July 3, 1951, Serial No. 234,925

5 Claims. (Cl. 300—4)

1

This invention relates to adhesive dispensing apparatus for brush making machines and more especially to an apparatus for automatically ejecting a predetermined amount of adhesive adjacent a brush back or blank prior to bristles being positioned in said brush back or blank by a brush making machine.

It is an object of this invention to provide a device adapted to be associated with conventional or other types of brush making machines wherein a bunch of bristles is fed to a bristle guide and at the same time, a wire staple is fed to the bristle guide and a plunger automatically positions the bristles with the wire staple thereabout in a brush back. The brush back may be circular or flat or of any desired configuration and is provided with a plurality of bores or holes therein adapted to receive the bristles. Now, in order to secure the bristles in the bores in the brush back, it has been found desirable and frequently necessary to put a drop of adhesive such as liquid glue in each of the bores to further secure the bristles within the bores. Heretofore, it has been necessary to place this glue in each bore in the brush back manually prior to the automatic operation of the brush making machine, which operation drives the bristles and staples into the bores in the brush back. This manual operation is costly and time consuming and the present invention which comprises a device for automatically ejecting or dispensing adhesive into the bores of the brush back upon operation of the brush making machine is provided to overcome the difficulties of the manual operation and to provide a faster more efficient means for adhesively securing bristles in a brush back than has heretofore been possible.

It is another object of this invention to provide a device adapted to be associated with a machine of the type described for positioning brush bristles in brush backs comprising means automatically operable by said machine for ejecting a drop of liquid glue into each bore in the brush back just prior to the bristles being positioned therein by the brush making machine and said device having cam means associated therewith driven by said machine to cause the same to operate in timed relation to the bristle positioning mechanism of said machine.

It is another object of this invention to provide in a machine of the type described having a bristle guide through which bristles are driven for positioning the same in a brush back, a bore in said bristle guide, a nozzle positioned in said

2

bore, and a plunger mechanism associated with said nozzle for ejecting adhesive through said nozzle into the bristle guide so that it will fall by gravity into a bore in the brush back and means associated with said machine for actuating said plunger mechanism to cause a predetermined amount of adhesive to be ejected by said nozzle into the bristle guide just prior to a bunch of bristles being driven through said bristle guide into a bore in said brush back.

It is another object of this invention to provide in a brush making machine of the type described, adhesive dispensing apparatus comprising a cylinder having a nozzle on one end thereof and a piston in the other end thereof and having means for introducing adhesive to the cylinder and said apparatus also being provided with cam means operatively connected to the drive means for said brush making machine for actuating said piston to cause a predetermined amount of adhesive to be ejected from said nozzle at predetermined intervals.

Some of the objects of the invention having been stated, other objects will appear as the description proceeds when taken in connection with the accompanying drawings, in which—

Figure 1 is an isometric view of the improved adhesive dispensing device showing parts of a brush making machine of the type with which the improved device may be associated and illustrating one type of brush back with which the invention may be used;

Figure 2 is a side elevation of the improved device on a reduced scale and showing associated parts of the illustrative brush making machine and brush back in dotted lines;

Figure 3 is a top plan view of the adhesive dispensing device and supporting bracket therefor disassociated from the brush making machine;

Figure 4 is a sectional view through the nozzle and plunger mechanism of the adhesive dispensing device taken along the line 4—4 in Figure 2.

For purposes of illustration only, there are shown parts of a brush making machine broadly designated at 10 which brush making machine may be of any desired conventional or other construction, it being understood that the present invention may be associated with various types of brush making machines and is not limited to use with the particular machine shown. Other machines of the type with which this invention may be used are illustrated in United States patents, Numbers 801,026, 845,959, 846,583, 869,313,

870,114, 906,246, 920,355, 1,125,136, 1,161,394 and 1,167,764. The particular driving means illustrated are shown and clearly described in Patent No. 801,026 and the particular type of brush illustrated in the drawings is shown clearly in Patent No. 1,125,136. A detailed description of these parts will not be given except as may be necessary to fully illustrate the operation of the present invention.

The brush making machine 10 may have a suitable table 11 on which the operative parts of the machine are positioned and the table 11 may be supported in any suitable manner. The table 11 is provided with a passageway 12 through which a sliding plunger or hammer 13 may have vertical sliding movement for driving bristles 14 through a bristle guide 15 into a bore 16 in a brush back or blank 17 to form tufts in said brush back. The bristle guide 15 is suitably secured to the lower surface of the table 11. The hammer 13 is slidably mounted in a vertically movable hammer block 20 which acts as a hammer guide and staple former and which is mounted in a guide block 21. The guide block 21 has a guide portion 22 extending from one side thereof which acts as a guide for bristles which are moved into position over the passageway 12 between the guide 22 and the upper surface of the table 11 prior to being driven through the bristle guide 15.

The bristles may be moved into this tuft forming position manually or by any suitable mechanism such as is more clearly illustrated in one or more of the above noted patents.

The guide block 21 has a cut away portion 23 through which a laterally movable anvil, not shown, has reciprocatory movement and a wire 24 is moved over the anvil, not shown, so that vertical movement of the plunger block 20 will cause a staple to be formed from said wire which staple is then driven over the bristles 14 by the plunger 13 as the plunger 13 drives the bristles through the bristle guide into the bores 16 in the brush back 17. The wire 24 is fed from a suitable source such as a reel, not shown, through a guide 25 positioned on a sliding wire actuator 26 slidably mounted in a guide 30 suitably positioned on the table 11 and a groove 31 in the table 11. The wire 24 also passes through a stop block 29 suitably secured to the guide 30 and the table 11. The sliding wire actuator 26 has a pair of movable jaws 32 and 33 which are adapted to grip the wire 24 and to move it through an adjustable shear block 34 adjustably mounted in the guide block 21. The sliding wire actuator is described in detail in said Patent No. 801,026 and is provided with an anti-friction roller 35 rotatably mounted thereon which is engaged by a cam 36 suitably journaled in a bearing block 37 fixed on the table 11.

The cam 36 is driven by suitable means, such as the means shown in said Patent No. 801,026 to cause the same to rotate in timed relation with the movement of the hammer 13 and the anvil, not shown, as well as the means for positioning bristles over the passageway 12 and it will readily be observed that as the cam 36 rotates in a counter-clockwise direction, the high point of the cam will urge the anti-friction roller 35 to the left in Figure 1 to cause the sliding wire actuator to slide in the guide 30 and groove 31 for moving a portion of the wire 24 through the opening 23 in the guide block 21 to be formed into a staple by the anvil, not shown, in a conventional manner.

In a brush making machine of the type where-in a round brush back 17 is used, the driving means for actuating the cam 36 also actuates suitable means for periodically rotating the brush back 17 so that a bore 16 will be positioned beneath the bristle guide 15 just prior to a bunch of bristles being moved through the bristle guide. Illustrative means for this purpose are clearly disclosed in Patent No. 1,125,136.

The parts heretofore described are conventional and it is with these parts or similar parts that the present invention is adapted to be associated.

Heretofore, in machines of this type, the bristles have been positioned in bores in a brush back in a manner described and stapled therein by the staples formed from the wire 24 but it has frequently been found desirable or necessary to provide additional means for securing bristles in a brush back such as the brush back 17. To this end, adhesive is usually applied to the bristles or the bores 16 in the brush back 17 so that the adhesive will serve to additionally secure the bristles in proper position. In order to put adhesive in the bores 16, it has heretofore been necessary for an operator to manually place a predetermined amount of adhesive in each bore 16 which has been a time consuming and expensive operation. It is to overcome the faults of this manual operation that the present invention is provided.

The improved glue ejecting device is broadly designated at 50 and has a bracket 51 for securing the same to the brush making machine 10 which bracket has a horizontal flange portion 52 and a vertical flange portion 53. The horizontal flange portion 52 is secured to the lower surface of the table 11 by any suitable means such as bolts 54. Suitably secured to the vertical flange portion 53 as by a screw 55 of the supporting bracket is a cylinder support plate 56. The flange 53 is preferably provided with a slot 57 which is penetrated by the screw 55 to permit adjustment of the cylinder support plate 56. The cylinder support plate 56 is provided with a pair of bearing blocks 58 and 59 suitably secured thereto as by welding. The bearing blocks 58 and 59 have fixedly mounted thereon as by set screws 59a a cylinder 60. The cylinder 60 is provided with a bore 61 in which a piston 62 has reciprocatory sliding movement. The left-hand end of the bore 61 in Figure 4 is threaded as at 63 for reception of a nipple 64. The nipple 64 has a nozzle 65 threadably mounted on the other end thereof. The nozzle 65 is provided with a glue ejecting bore 66 and a chamber 67 communicating with the glue ejecting bore 66 and a bore 64a through the nipple 64. The outer end of the nozzle is reduced as at 68 for purposes to be described. The bore 64a in the nipple 64 is of a smaller diameter than the chamber 67 and a ball 70 is held in engagement therewith by a spring 71 which thus operates as a check valve.

The cylinder 60 is provided with a bore 75 therein in which is positioned one end of an adhesive line 76 suitably secured therein as by welding and the other end of the adhesive line 76 is removably secured in the bottom of an adhesive container 77 as by a coupling 78, the line 76 communicating with the interior of the adhesive container 77. The adhesive container is provided as a source of adhesive such as liquid glue, not shown, and the upper end of the adhesive container 77 is provided with a threaded

bore in which is mounted a threaded plug 80 which has a breather hole 81 therein and which plug 80 may be removed to permit additional adhesive to be placed in the container 77.

The adhesive container 77 may be supported solely by the line 76 or if desired suitable bracket means or the like, not shown, may be utilized to connect the adhesive container 77 to the brush making machine.

The end of the piston 62 remote from the cylinder 70 is adjustably mounted in an adjustment block 85 as by a set screw 86. The adjustment block 85 also has one end of a plunger 87 adjustably mounted therein as by a set screw 88. The plunger 87 extends through a tubular guide or sleeve 90 fixedly mounted in a plunger support block 91 as by a set screw 89 and the block 91 is suitably secured to the vertical flange 53 of the bracket 51 as by screws 92. The flange 53 preferably has slots 93 therein which are penetrated by the screws 92 to permit adjustment of the plunger support block 91 on the bracket 51. The upper end of the plunger 87 is provided with a plate-like cam follower portion 94 and a compression spring 95 is positioned about the upper end of the plunger 87 and is confined between the plate-like cam follower portion 94 and the upper end of the tubular sleeve 90. The sleeve 90 may be adjusted in the plunger support block 91 by the set screw 89 to vary the tension of the spring 95. The plunger 87 has sliding movement in the tubular sleeve 90 and is normally urged upwardly or to the right in Figures 1, 2 and 3 by the compression spring 95.

The conventional cam 36 on the brush making machine for actuating the sliding wire actuator is mounted on a rotating shaft, not shown, and suitably secured to this cam 36 or to the shaft on which it is mounted, as by said shaft being provided with an internally threaded bore, is the threaded end of a cap screw or cam shaft 100 which is surrounded by a sleeve 101 and which has a cam 102 held in position against the outer end thereof by the head of the cap screw. The sleeve 101 serves to space the cam 102 from the cam 36 and the cap screw 100 will cause the cam 102 to rotate with the cam 36. It will be noted that the high point of the cam 102 is positioned oppositely to the high point of the cam 36 so that the cam 102 will cause actuation of the glue dispensing device just prior to movement of the sliding wire actuator by the cam 36.

Obviously, the cam 102 may be adjusted as desired to cause actuation of the adhesive dispensing device at any desired time relative to other movements of the brush making machine. The high point of the cam 102 engages the plate-like cam follower surface 94 of the plunger 87 to cause the plunger 87 to move downwardly or to the left in Figures 1, 2 and 3 to cause the piston 62 to move inwardly or to the left in Figure 4 in the cylinder 60 to thus force adhesive, which has been moved by gravity through the pipe 76 into the chamber 61 in the cylinder 60, against the spring pressed ball 70 and out through the nozzle bore 66. The reduced end portion 68 of the nozzle 65 is provided to be inserted in a bore 105 which is provided in one side of the bristle guide 15.

With the portion 68 of the nozzle positioned in the bore 105 in the bristle guide, it will be observed that adhesive emitted from the nozzle bore 65 will pass through the bore 105 into the interior of the bristle guide and will fall, by gravity, therethrough into the bore 16 of the

brush 17 which is positioned immediately below the bristle guide. After the adhesive has been ejected into the bristle guide, the bunch of bristles will be driven through the bristle guide by the hammer 13 in a conventional manner into the bore 16 and as the bristles move through the guide 15, they will wipe any excess adhesive from the interior of the guide 15.

The adjustment block 85 is provided to adjust the length of stroke of the piston 62 so that any desired amount of adhesive may be emitted from the nozzle 64 according to various requirements.

It is thus seen that there is provided in a brush making machine having a bristle guide and plunger mechanism for driving bristles through said bristle guide and means for forming a wire staple for each of said bristles, improved glue dispensing means actuated by said means for forming said staple comprising a cylinder, a plunger reciprocally mounted in said cylinder, a nozzle mounted on one end of said cylinder, means for introducing adhesive to said cylinder, and plunger means for actuating said piston for ejecting adhesive from said cylinder through said nozzle into said bristle guide from whence the adhesive is positioned in bores in a brush back prior to bristles being positioned in said bores.

In the drawings and specification, there has been set forth a preferred embodiment of the invention and although specific terms are employed, they are used in a generic and descriptive sense only and not for purposes of limitations, the scope of the invention being defined in the claims.

I claim:

1. In a brush making machine for inserting bristles into bores in a brush blank and having a bristle guide provided with a longitudinally extending passageway for bristles, a hammer for driving bristles through said bristle guide and said machine also having a wire actuator for forming bristle holding staples driven in timed relation to said hammer and means for driving said machine including a first cam for actuating said wire actuator; adhesive dispensing means comprising a bracket secured to said machine, a plate adjustably secured to said bracket, a cylinder mounted on said plate, a nozzle secured to one end of said cylinder and communicating with the interior thereof, the bristle guide having a bore in one side thereof communicating with the passageway, the ejection end of said nozzle being positioned in the bore in the side of the bristle guide, means for introducing adhesive to said cylinder, a piston reciprocally mounted in said cylinder, a plunger support block adjustably secured to said bracket, a plunger slidably mounted in said plunger support block, said plunger being parallel to and adjustably connected to said piston, a second cam, means connecting the second cam to the first cam, said second cam being positioned in alignment with said plunger, whereby rotation of said wire actuator cam will cause rotation of said second cam to actuate said plunger and said piston in said cylinder to dispense a predetermined amount of adhesive from the nozzle on said cylinder, and spring means positioned about said plunger and normally urging said plunger toward said second cam.
2. In a brush making machine for inserting bristles into bores in a brush blank and having a bristle guide provided with a longitudinally

extending passageway for bristles, a hammer for driving bristles through said bristle guide and said machine also having a wire actuator for forming bristle holding staples driven in timed relation to said hammer and means for driving said machine including a first cam for actuating said wire actuator; said bristle guide having a bore in one side thereof communicating with the passageway, adhesive dispensing means comprising a bracket secured to said machine, a plate adjustably secured to said bracket, a cylinder mounted on said plate, a nozzle secured to one end of said cylinder and communicating with the interior thereof, the ejection end of said nozzle being positioned in the bore in the side of the bristle guide, means for introducing adhesive to said cylinder, a piston reciprocally mounted in said cylinder, a plunger support block adjustably secured to said bracket, a plunger slidably mounted in said plunger support block, said plunger being parallel to and adjustably connected to said piston, a second cam, means connecting the second cam to the first cam, said second cam being positioned in alignment with said plunger, whereby rotation of said wire actuator cam will cause rotation of said second cam to actuate said plunger and said piston in said cylinder to dispense a predetermined amount of adhesive from the nozzle on said cylinder, and said means for introducing adhesive into said cylinder comprising an adhesive storage tank, a line communicating with said adhesive storage tank and with said cylinder and serving as a support for said cylinder.

3. In a brush making machine for inserting bristles into bores in a brush blank and having a bristle guide provided with a longitudinally extending passageway for bristles, a hammer for driving bristles through said bristle guide and said machine also having a wire actuator for forming bristle securing staples driven in timed relation to said hammer and means for driving said machine including a first cam for actuating said wire actuator; said bristle guide having a bore in one side thereof communicating with said passageway, means for dispensing predetermined amounts of adhesive in timed relation to the operation of said machine, comprising a bracket secured to said machine, a cylinder adjustably mounted on said bracket, a nozzle secured to one end of said cylinder and communicating with the interior thereof, the ejection end of said nozzle being positioned in the bore in one side of the bristle guide, means for introducing adhesive to said cylinder, a piston reciprocally mounted in said cylinder, a plunger adjustably and slidably supported by said bracket, said plunger being adjustably connected to said piston and disposed in overlapping relation thereto, a second cam, a shaft adjustably connecting said second cam to said first cam for actuating said wire actuator, said second cam being positioned in alignment with said plunger, said plunger having a cam follower on the end thereof which is engaged by said second cam and spring means positioned about said plunger and normally urging the same toward the second cam, whereby rotation of said first cam will cause rotation of said second cam to actuate said plunger and said piston in said cylinder to dispense a predetermined amount of adhesive from the nozzle on said cylinder.

4. In a brush making machine for inserting bristles into bores in a brush blank and having

a bristle guide provided with a longitudinally extending passageway, a hammer for driving bristles through said bristle guide and said machine also having a wire actuator for forming bristle securing staples driven in timed relation to said hammer and means for driving said machine including a first cam for actuating said wire actuator; said bristle guide having a bore in one side thereof communicating with said passageway, means for dispensing predetermined amounts of adhesive in timed relation to the operation of said machine, comprising a bracket secured to said machine, a cylinder adjustably mounted on said bracket, a nozzle secured to one end of said cylinder and communicating with the interior thereof, the ejection end of said nozzle being positioned in said bore in one side of the bristle guide, means for introducing adhesive to said cylinder, a piston reciprocally mounted in said cylinder, a plunger adjustably and slidably supported by said bracket, said plunger being adjustably connected to said piston, a second cam, a shaft adjustably connecting said second cam to said first cam, said second cam being positioned in alignment with said plunger, said plunger having a cam follower on the end thereof which is engaged by said second cam, spring means positioned about said plunger and normally urging the same toward the second cam, whereby rotation of said first cam will cause rotation of said second cam to actuate said plunger and said piston in said cylinder to dispense a predetermined amount of adhesive from the nozzle on said cylinder and said means for introducing adhesive into said cylinder comprising an adhesive storage tank, a line communicating with said adhesive storage tank and with said cylinder and serving as a support for said cylinder.

5. In a brush making machine for inserting bristles into bores in a brush blank and having a bristle guide provided with a longitudinally extending passageway and a hammer for driving bristles through said bristle guide and said machine also having a wire actuator for forming bristle securing staples driven in timed relation to said hammer and means for driving said machine including a first cam for actuating said wire actuator; said bristle guide having a bore in one side thereof communicating with said passageway, means for dispensing a predetermined amount of adhesive adjacent said bristle guide in timed relation to the operation of said machine to assist in securing said bristles in said brush blank, comprising a bracket secured to said machine, a plate adjustably secured to said bracket, a cylinder mounted on said plate, a nozzle secured to one end of said cylinder and communicating with the interior thereof, the ejection end of said nozzle being positioned in said bore in the bristle guide, means for introducing liquid adhesive to said cylinder, a plunger support plate adjustably connected to said bracket, a sleeve adjustably mounted in said plunger support plate, a plunger slidably mounted in said sleeve, a piston slidably mounted in said cylinder, an adjustment block for adjustably connecting said piston and said plunger, one end of said sleeve serving to engage said adjustment block to limit sliding movement of said plunger in said sleeve, the end of said plunger remote from said piston being provided with a cam engaging surface, a second cam adjustably con-

nected to said first cam whereby the second cam will rotate with said first-named cam, said second cam being positioned in alinement with the cam engaging surface of said plunger in said sleeve to actuate said piston in said cylinder for dispensing adhesive and a spring positioned about said plunger and bearing against one end of said sleeve and against said cam engaging surface for normally urging said plunger into engagement with said second cam.
